No. 836,626.

PATENTED NOV. 20, 1906.

D. BROADBELT.

GARTER.

APPLICATION FILED NOV. 9, 1905.

UNITED STATES PATENT OFFICE.

DANIEL BROADBELT, OF NEW YORK, N. Y.

GARTER.

No. 836,626.

Specification of Letters Patent.

Patented Nov. 20, 1906.

Application filed November 9, 1905. Serial No. 286,621.

To all whom it may concern:

Be it known that I, DANIEL BROADBELT, a citizen of the United States, and a resident of the city of New York, borough of Brooklyn, in the county and State of New York, have invented a new and Improved Garter, of which the following is a full, clear, and exact description.

My invention relates to garters and the like, my more particular object being to produce a type of garter in which there is a laterally-resilient portion which may be extended or contracted at will, and provided with a longitudinally-resilient elastic portion which may be extended and of itself returns to its original shape.

My invention further embraces certain improvements whereby the garter may be connected with the hose or other garment and readily disconnected therefrom.

Reference is to be had to the accompanying drawings, forming a part of this specification, in which similar characters of reference indicate corresponding parts in all the figures.

Figure 1 is a perspective showing the complete device in use. Fig. 2 is an enlarged perspective view showing the garter and its accompanying parts removed. Fig. 3 is a vertical section through the fastening member used for securing the hose to the garter. Fig. 4 is an enlarged section upon the line 4-4 of Fig. 2 looking in the direction of the arrow and showing the clamp for holding the laterally-resilient members of the garter; and Fig. 5 is a central horizontal section through a portion of the garter, showing the clamp 9 for holding the two laterally-resilient members 6, 7.

A band formed of metal, whalebone, or sheet material of almost any kind is composed of a plurality of sections 6, 7, the sections being adapted to slide relatively to each other. The section 6 carries a bracket 8, which serves as a hinge and supports a clamp 9. The latter is provided with a stem 11, having a flat portion 10, as will be understood from Fig. 5. The section 7 is provided with ears 12, connected rigidly thereto and bent partially over and within the section 6, as indicated in Fig. 2. The ears 12 virtually constitute a slide for enabling the sections 7 and 6 to move relatively to each other. An elastic band 13 engages a button 14, mounted rigidly upon the section 7,

This elastic band 13 is passed through the end of the section 6 at the point 15, as will be understood from Fig. 2. A buckle 16 enables the elastic band 13 to be lengthened or shortened, as desired. The normal position 60 of the link 9 for clamping the members 6, 7 firmly together is indicated in Figs. 2 and 5.

In order to enable the sections 6, 7 to be moved relatively to each other, the operator grasps the link 9 and swings it angularly outward, the position indicated in Fig. 4. This brings the flat face 10 of the portion 11 parallel with the outer surface of the section 7, and the sections 6, 7 may therefore be moved relatively to each other, this movement being permitted by the slide 12, as above explained. It follows, therefore, that the laterally-resilient portion of the garter may be given any desired aggregate length, the elastic band 13 allowing for a reasonable degree of expansion and contraction of the garter as a whole. The section 7 is provided with a slot 17, and threaded through the slot is a double cord 18, which is provided with looped portions 18^a, 18^b. The loop portion 80 18^b engages a link 19, of metal. This link is provided with eyes 19^a and with an end portion 19^b, which serves as a pivot for a plate 20, depending therefrom. Mounted upon this plate is a button 21, which is engaged by 85 a swinging link 22, as indicated in Figs. 2 and 3.

In order to connect the parts shown in Fig. 3 with the hose or similar article of clothing, the plate 20 is slipped upon the side of the article, the cloth of the latter being thus caused to cover the button 21. The link 19 is then bent outward, as indicated by full lines in Fig. 3, and the link 22 is pressed around the button, or rather around the cloth covering 90 the button, and the link 19 is then straightened out, as indicated by dotted lines in Fig. 3. This causes the link 22 to exert a comparatively firm pressure relatively to the button 21, so as to grip the hose or similar article and hold the same securely.

In order to remove the garter, the operator merely removes the elastic band 13 from the button 14 and then bends the link 19 angularly outward, as indicated in Fig. 3. 105 This leaves all parts of the garter and its appendages entirely free.

It will be noted that in the device above described not only may the garter proper or annular member be made larger or smaller by 110

adjusting the laterally-resilient members 6 7, but that when this result is accomplished the elasticity of the band 13 may be relied upon to perform its usual office, and this band may be adjusted at will.

- 5 If the garter is too small for a given person and the elastic band is contracted accordingly, the members 6 7, unless properly adjusted, would constitute too large a proportion of the garter. For instance, in some cases the button 14 might be comparatively near the portion 15, and this would impair the elasticity of the garter as a whole. This difficulty is avoided by the adjustment of the laterally-resilient parts 6 7 of the garter. It will be seen, therefore, that the garter may be adjusted to various diameters and yet may preserve the relative proportions as between its inflexible and flexible portions.
- 10 20 By removing the cord 18 and the metallic parts depending therefrom the circular member shown in the upper part of Fig. 2 may be used as an armlet. I do not limit myself, therefore, to any particular use to which my invention or any part thereof may be devoted.
- 15 25 Having thus described my invention, I

claim as new and desire to secure by Letters Patent—

1. In a garter, the combination of a plurality of sections having their adjacent ends overlapping and movable longitudinally of each other whereby to vary the aggregated length of the sections, one of said sections having lateral ears partially inclosing the other section, a clamp for fixing said members with respect to each other, and an elastic band connecting the free ends of the sections.

2. In a garter, the combination of a band comprising a plurality of sections having their adjacent ends overlapping, means for slidably connecting the sections, a clamp for fixing the sections with respect to each other, and an elastic band connecting the free ends of the sections.

In testimony whereof I have signed my name to this specification in the presence of two subscribing witnesses.

DANIEL BROADBELT.
